CLAIM

The ornamental design for a table, as shown and described.

DESCRIPTION

FIG. 1 is a front perspective view of a table;

FIG. 2 is a front elevation view thereof;

FIG. 3 is a back elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken line showing of elements on the table illustrates portions of the article and forms no part of the claimed design.
